INVENTOR.

William E. Goodenough

United States Patent Office.

WILLIAM E. GOODENOUGH, OF NEWARK, NEW JERSEY.

Letters Patent No. 82,825, dated October 6, 1868.

IMPROVEMENT IN SAW-SET.

The Schedule referred to in these Letters Patent and making part of the same.

TO ALL WHOM IT MAY CONCERN:

Be it known that I, WILLIAM E. GOODENOUGH, of Newark, in the county of Essex, and State of New Jersey, have invented a new and improved Saw-Set; and I do hereby declare that the following is a full, clear, and exact description of the same, reference being had to the accompanying drawings, forming a part of this specification, in which—

Figure 1 represents a longitudinal vertical section view of a saw-set constructed according to my improvement, with the upper side of the handle or stock removed.

Figure 2 represents a top, and

Figure 3 represents a transverse section, taken through the line $z z$, illustrating the mode of applying it to the saw.

Similar letters of reference indicate corresponding parts in the several figures.

The object of this invention is to provide for setting the teeth of saws to an absolute uniformity, with greater facility than is afforded by the saw-sets in common use, and without drawing or flattening the tooth.

The invention consists in a novel arrangement of the several parts of a saw-set, whereby the pulling of a trigger-like lever elevates and releases a pivoted hammer, which, by means of a spring-attachment, descends upon said releasement, thereby striking the tooth of the saw, while the blade thereof serves as a guide to the set.

In order that others may be better enabled to understand the construction and operation of my invention, I will proceed to describe it with reference to the drawings.

A is the stock or body of the saw-set, of a formation much resembling that of a pistol-stock. B is a pivoted arm or hammer, which is operated by means of a main spring, b, after a manner substantially the same as the hammer of a pistol, and which is provided with cogged sector upon its lower part, partially surrounding the pivot f. C is a forked lever or trigger, with its pivot d in front of the pivot f of the hammer B. This lever or trigger C has upon its lower extremity a ring for insertion of the finger, and which projects from the under side of the stock for that purpose, and is made double, or bipronged, along its central and upper portion, for the purpose of receiving between said prongs a cogged sector, D, which has its pivot in common with the pivot d of the trigger C, but has a separate and independent motion from the same. This cogged sector D engages, by means of its cogs, with the cogs of the sector E, upon the lower part of the hammer B, and has secured to it at its upper extremity a curved spring, e, which is provided with a hook or notch, i, and a projection, h, extending beyond the said notch i, for a purpose hereinafter explained. The upper extremities of the prongs of the fork of the trigger C are made to project a little above the pivot d, and turn forwards by an abrupt turn to the left, as shown at fig. 1. The extreme upper points of these prongs are connected together by a stud or pin, a, so that when the trigger C is drawn backwards, thereby throwing the upper ends of the forks forward, this pin or stud a locks into the notch i on the under side of the curved spring e, carrying forward the sector D, thereby raising the hammer B.

e is a stud or bolt passing transversely through curved slots o in the stock A, in a horizontal direction. This stud is situated in front of the pivot d, and immediately below the projection h of the spring e, and is susceptible of a nearly vertical adjustment in the slots o, and therein secured by a nut, g, on one end, and a head upon the other, so that when the lever or trigger C is drawn back, carrying the sector D forward by lock of the stud or pin a with the notch i of the spring e, and thereby raises the hammer B, the projection h is brought in contact with the stud e, whereupon, a continued pull upon the trigger C carries the spring forward, and forces the projection h against the stud e with sufficient force to cause the spring e to yield, and the pin a to become disengaged from the notch on the said spring. The hammer B being thereby released, is carried downward by means of the main spring b, inflicting a blow upon the tooth of the saw with a degree of force proportionate to the degree of elevation to which the hammer is raised, which is regulated by adjustment of the stud or bolt e in the slots o, nearer to or further from the projection h.

On releasing the trigger C, it is caused to resume its former position by means of a spiral spring, k, one

extremity of which is attached to the said trigger, the other to a part of the stock A, in front of the said trigger C.

m is a guide, secured to and firmly between the extremities of the arms A' of the stock A, and situated in a perpendicular relation to the plane of motion, and against which the sides of the saw-teeth are kept when the saw is being set, and which receives the recoil of the hammer when the tooth is struck, thereby preventing the tooth from being broken off or set too far. *n n* are friction guide-rollers, carried upon an adjustable frame, *p*, which is susceptible of elevation and depression, by means of a vertical slot in its centre, and between the guide-rollers *n n*, and through this slot passes the set-screw *S*, which serves to secure the said frame to the guide-bar *m*.

The guide-rollers *n n* serve as guides to the upper edge of the teeth, and regulate the upward motion of the saw.

The aforesaid adjustment of the said rollers is provided for the purpose of setting saws having larger or smaller-sized teeth, and which may be raised or lowered for said purpose, and when suitably adjusted to the teeth, may be secured at said adjustment by means of the set-screw *S*, tightened upon the frame *p*.

W is a lower guide-roller, carried upon the outer end of an adjustable arm, *y*, which projects from the stock under the hammer, and parallel with the same, and which serves to guide the blade of the saw and regulate the amount of set given to the teeth, its adjustability for that purpose being effected by means of a longitudinal slot through the arm *y*, through which fits a headed bolt. The adjustment of said roller, when made, is secured by a set-screw, *V*, upon the outer extremity of said bolt.

Z is a set-screw, in the lower part of the handle or stock, for the purpose of tightening and strengthening the main spring *b*.

When this saw-set is to be used or operated, the saw requiring to be set is secured in a vise, or otherwise suitably confined, with its teeth upward, and the saw-set so grasped in the hand that the index or fore-finger may be passed through the ring of the trigger C. A partial contraction of the finger upon said trigger will slightly elevate the hammer, so that the face thereof will clear the face of the guide *m*, whereupon the device may be placed upon the edge of the saw, so that the inner side or guiding face of the bar *m* rests against the opposite side of the teeth, the guide-rollers *n n* resting upon the upper edge of the saw, and between the points of the teeth, and the guide-roller *W* resting against the near side of the saw-blade, or the side opposite that operated upon by the guide *m*.

When in this position, and adjusted upon the first tooth to be set, the trigger C is pulled backwards far enough, not only to elevate, but to release the hammer B, which descends upon the tooth, driving it against the face of the guide *m*, thereby giving said tooth a degree of set proportionate to the adjustment of the device, after which the hammer is again withdrawn by the same means already described, and the device adjusted upon the tooth next to be set, and the hammer caused to rise and descend as before, and so on, until the operation is completed.

A partial backward tension of the trigger C, and the consequent result thereof, are illustrated by those parts of fig. 1 represented in red outline.

What I claim as my invention, and desire to have secured by Letters Patent, is—

1. The combination of the guide-bar *m* and adjustable frame *p*, carrying the guide-rollers *n n*, with the stock A, hammer B, and adjustable guide-roller *W*, all arranged and operating substantially as shown and described.

2. The spring *c* having a projection, *h*, and notch *i*, attached to the sector D, in combination with the stud *a* on the trigger; and adjustable stud *e*, for operation together, substantially as set forth.

WILLIAM E. GOODENOUGH.
